DIPPER HANDLE

Einar G. Hallquist, Wallingford, Pa., assignor to
General Steel Castings Corporation, Granite
City, Ill., a corporation of Delaware

Application October 19, 1932, Serial No. 638,581

14 Claims. (Cl. 214—145)

This invention relates to dredge or other power shovels and consists particularly in a novel dipper handle.

In dredge and other power shovel construction, it is desirable that moving parts, such as the dipper handle, be as light as possible while at the same time sufficiently strong to withstand the various twisting, bending and rack forces incident to the hard usage to which the part is subjected. Since these forces vary at different points along the handle, a different disposition of metal is desirable at the different points in order to adequately withstand the various stresses without unduly increasing the size and weight of the part.

In built-up structures, the wall thicknesses are increased to conform with the varying strength requirements, by the addition of plates at the portions subjected to greatest moments of force, but the moments of force applied to this type of structure produce stresses which vary at different points along the walls. The stresses are greatest at the points of greatest moments and decrease uniformly to the ends of the plates where concentration of stresses occurs due to the sharp offsets in the wall thicknesses. In the walls of a cast structure, no discontinuity or sharp offsets will occur.

It has been found that the dipper or outer end of the handle is subjected to rotational or twisting forces due to eccentric digging of the shovel; that is, digging on one corner only instead of straight across the front edge thereof. The greatest bending forces are applied to the inner end of the handle and these are applied vertically during digging and laterally when the boom swings to the side and causes the shovel to strike the materials to be removed.

Moreover, due to the sudden shocks received in operation, the handle should be made as flexible as possible throughout, and it is difficult in the ordinary built-up structures to provide for uniformity of stress and to so arrange the metal plates as to provide adequate strength and ruggedness without a consequent loss of flexibility and lightness, and vice versa.

The twisting forces at the dipper end of the handle are best resisted by a substantially cylindrical disposition of metal. The bending and rack forces at the boom end are best resisted by a handle of rectangular section, and also the rectangular section facilitates the application of the gear racks and provides better bearing against the guides or ways of the boom.

One object of the present invention is to pro-

vide a dipper handle suitably shaped at various points to accommodate the different forces referred to.

Another object is to provide a dipper handle which shall be as light and flexible as possible commensurate with the strength requirements.

Another object is to provide a cast dipper handle structure which is varied in cross section and thickness of wall in a manner to obtain a substantially uniform or constant stress due to the forces applied to the various parts thereof.

Another object is to construct a one-piece dipper handle having no joints or crevices weakening the structure and necessitating frequent inspection and repairs.

These objects and others are attained substantially by the structures illustrated in the accompanying drawings in which—

Figure 1 is a half side view of the novel dipper handle.

Figure 2 is a similar view of the other half thereof.

Figure 3 is a half top view of the handle.

Figure 4 is a similar view showing the other half of the handle.

Figures 5 and 6 are vertical longitudinal sections taken on the corresponding section lines of Figures 3 and 4, respectively.

Figure 7 is a transverse section taken on the broken line 7—7 of Figure 4.

Figure 8 is an end view of the handle.

Figure 9 is a vertical transverse sectional view taken on line 9—9 of Figure 1.

Figures 10, 11 and 12 are similar views taken on the corresponding section lines of Figure 2.

Figure 13 shows the novel dipper handle assembled with a boom and other dredge parts upon a dredge hull.

Figure 14 is a detail vertical longitudinal section through a modified form of the handle.

Figure 15 is a transverse section taken on the line 15—15 of Figure 14.

The handle is illustrated as cast in one piece including a rectangular portion extending substantially half the length of the structure and having side walls 1, top wall 2, and bottom wall 3 to which is secured a rack plate 4, parts of which are shown in Figures 1 and 5. Projections 10 and 20 at the end of the rack plate prevent the co-operating pinion gear (not shown) from running off the end of the rack. This part of the structure is reinforced by transverse ribs 5 having substantial central perforations 5a.

At the opposite end of the handle is a downwardly inclined box-shaped part 6 provided with

lugs 6a for pivotally mounting the dipper 9 (Figure 13), and ears 7 forming pockets for mounting dipper braces 8. As indicated in Figure 12, the handle immediately adjacent the dipper supporting elements is of circular cross section to better resist twisting forces centered about this portion. As indicated in Figures 12, 11, and 10, respectively, the cross-sectional shaping towards the middle gradually assumes the oblong shape 10 of the rack portion, as in Figure 9. Lateral bending moments in the handle decrease towards the dipper end, permitting the use of less metal at this end and, accordingly, the cross-sectional area of the metal at the dipper end is made less than 15 that of the rectangular rack portion, the cross-sectional area gradually decreasing from the inner end 10 of the rack to the lugs 7. The vertical dimension of the tapering part varies, as in Figure 2, while the horizontal dimension remains substantially constant from end to end of the handle. The rack portion at the left-hand end is of 20 uniform cross-sectional area.

The walls of the rack portion are of suitable thickness to withstand the bending stress referred to and the thrust arising from operation of the rack and pinion drive, and the handle walls are uniformly decreased in thickness from end wall 21 towards the dipper end, reaching a minimum thickness adjacent the lugs 7. A portion of 25 the wall, particularly at the boom end, may be made of uniform thickness, if desired. This construction provides for maximum flexibility at the outer end of the handle adjacent the dipper supporting part, together with uniform stress and 30 adequate strength throughout. The side walls are provided with perforations 11 to lighten the structure and permit access to the interior thereof, the top and bottom walls being imperforate from end to end. The lower surface is suitably machined 35 for mounting the rack 4 which may be welded or otherwise secured in position. The corners of the rectangular rack portion are rounded, as at 12, to limit stress concentration which would result if the horizontal and vertical walls met in sharp 40 corners.

In Figures 14 and 15, the under surface of the inner half portion 13 of the handle structure is provided with integral transverse corrugations 45 forming a rack for engaging the operating gear on the boom. The structure is otherwise the same as in the previous form.

Figure 13 shows the novel handle, indicated generally at 15, assembled with the dipper 9 and boom 16 and mounted on a dredge hull 17 which is anchored to the bottom by one or more of the spuds 18. It will be seen that during the digging operation when the dipper is in its lowest position, 50 forces on the handle will be at the maximum, while in the raised position of the dipper most of the forces will be carried by the lifting cable 19, operated by an engine or motor on the dredge hull, shown in part at 23.

The novel handle is suitably shaped throughout 55 to adequately withstand the varying stresses applied to different parts thereof. There are no overlapping flanged joints incident to built-up constructions and the metal is disposed in the most advantageous manner so that the structure attains the maximum lightness and flexibility. Various features of the invention are best 60 attained by the integral construction shown and described, and the consequent absence of bolted and riveted connections substantially increases 65 the strength and durability of the structure, which

should last the lifetime of the dredge or power shovel.

The detail shaping of the handle illustrated is not essential. For instance, the gradually diminishing area of cross section may vary in its horizontal dimension instead of its vertical dimension as shown, or it may vary in both dimensions. Also the dipper mounting elements are not essential and these may be otherwise shaped and disposed, or may be formed separately and riveted or welded to the handle. The novel handle may be advantageously used in all forms of power shovels. These and other modifications may be made without departing from the spirit of the invention and I contemplate the exclusive use of all such modifications as come within the scope of the appended claims.

What is claimed is:

1. A dipper handle having a rack portion and a dipper mounting portion, said dipper portion having walls substantially curved in a plane transverse to the axis of the handle and said rack portion having flat walls. 95
2. A dipper handle having a rack portion and a dipper mounting portion, the cross-section of said dipper portion being of circular shape and the cross-section of said rack portion being of rectangular shape. 100
3. A dipper handle having a rack end and a dipper end, the cross-section of the handle at said dipper end being circular and gradually changing to substantially rectangular shape at said rack end. 105
4. A dipper handle including a rack portion of substantially rectangular cross-section, and a dipper mounting end spaced therefrom, the cross-sections between said portion and said end gradually changing from rectangular to circular shape. 110
5. A dipper handle including a rack portion and a dipper mounting portion, the cross-sections of the metal between said portions gradually changing from rectangular to circular shape and gradually decreasing in area. 115
6. An integral hollow dipper handle structure including a rack portion and a dipper mounting part, the cross-sectional area of the structure being circular at said part and gradually changing to rectangular at said portion, and the wall thickness of the structure gradually increasing from said part to said portion. 120
7. An integral dipper handle structure including a dipper mounting part of round cross-section to withstand torsional forces and a rack portion of rectangular cross-section to withstand bending forces and with its corners rounded to limit stress concentration. 130
8. In a handle for a power dipper, an end part including elements spaced substantially from each other longitudinally of the handle for mounting a dipper, a part spaced from said end part for a rack by which the handle and dipper mounted thereon are manipulated, and a structure of substantial length between said parts and constructed so that its portion adjacent to said dipper mounting end part may flex in different angular directions about the handle axis more readily than the portion of said structure adjacent said rack part. 135
9. In a handle for a power dipper, an end part including elements spaced substantially from each other longitudinally of the handle for mounting a dipper, a part spaced from said end part for a rack by which the handle and dipper mounted thereon are manipulated, and a structure 140
- 145
- 150

of substantial length between said parts and comprising webs disposed in different planes transversely of the handle axis and decreasing in thickness towards said dipper mounting end sufficiently to render the handle flexible to accommodate blows against the dipper.

10. A handle for a power dipper comprising an end part upon which the dipper may be mounted and of rigid construction to resist deformation under forces to which the dipper is subjected, and a body part of hollow metal construction and tapering towards said end part so that the portion of said body part adjacent to said end part is more flexible than the remainder thereof and adapted to flex under said forces.

11. A handle as specified in claim 10 in which the walls of hollow body part decrease in thickness towards the end part for mounting the dipper.

20 12. A handle for a power dipper comprising an end part upon which the dipper may be mounted and of rigid construction to resist deformation under forces to which the dipper is subjected, a rack part spaced substantially from said end part 25 and of rigid construction to resist such deformation transversely of its axis as would affect free operation of the rack and its pinion, and an intermediate part of hollow section of substantial

width to resist torsional stresses arising from forces tending to twist the dipper about the longitudinal axis of the handle, said intermediate part having a cross sectional area adjacent to said end part less than its cross sectional area adjacent said rack part, the length of said intermediate part and the variation in its cross sectional areas being proportioned to provide flexibility transversely of said axis adjacent said end part to yield to blows on the dipper applied at different angles.

13. A handle as specified in claim 12 in which the walls of the hollow intermediate part decrease in thickness towards the end part for mounting the dipper.

14. A handle for a power dipper having an end part for mounting the dipper, a rack part spaced therefrom, and an intermediate part of substantial length between said end part and said rack part and having a substantially circular cross section adjacent to said end part and with its cross section gradually changing to a substantially rectangular cross section towards said rack part, the cross section of said end part being non-circular.
